UNITED STATES PATENT OFFICE

ARTHUR STOCKSTROM, OF ST. LOUIS, MISSOURI, ASSIGNOR TO AMERICAN STOVE COMPANY, OF ST. LOUIS, MISSOURI, A CORPORATION OF NEW JERSEY

DESIGN FOR A SET OF RANGE DOORS

Application filed July 10, 1931. Serial No. 40,489. Term of patent 14 years.

To all whom it may concern:

Be it known that I, ARTHUR STOCKSTROM, a citizen of the United States, residing in the city of St. Louis and State of Missouri, have invented a new, original, and ornamental Design for a Set of Range Doors, of which the following is a specification, reference being had therein to the accompanying drawing.

The accompanying drawing is a perspective view of the set of range doors, showing my new design.

The characteristic feature of my design

is providing the set of doors with a representation of tiles arranged around the edge of the doors leaving a plain central portion, which produces a unitary article of manufacture.

I claim:

The ornamental design for a set of range doors substantially as shown and described.

In testimony whereof, I hereunto affix my signature.

ARTHUR STOCKSTROM
